UNITED STATES PATENT OFFICE

GEORGE W. MILLER, OF KANSAS CITY, MISSOURI

BRAKE-BEAM HANGER

Application filed December 4, 1928. Serial No. 323,691.

This invention relates to a brake beam hanger particularly adapted for use in connection with the brake beams of railroad cars, locomotives and street cars, but it is to be understood that my improved hanger may be employed in any capacity for which the same is found to be applicable.

The primary object of the invention is to provide, in a manner as hereinafter set forth, a brake beam hanger of the type employing a hanger member and a pin secured thereto by cotter keys, and including as a part thereof, means for preventing the turning of the pin relative to the hanger, thereby eliminating any possibility of the cotter keys being closed and worked out of position, due to such relative movement of the pin.

A further object of the invention is to provide a brake beam hanger as aforesaid, by means of which the pin for the hanger member may be positioned to maintain the cotter keys in a vertical position, thereby preventing the keys from falling out, should they become closed from any cause.

25 A further object of the invention is to provide a brake beam hanger as aforesaid wherein the hanger member and pin are secured by a pair of cotter keys and interlocked in such a manner as to be securely held by either of said keys, should the other of said keys, for any reason, become dislodged.

30 A further object of the invention is to provide a brake beam hanger as aforesaid which is simple in construction, economical to manufacture, strong, durable, thoroughly efficient in its intended use, and convenient in its application.

With the foregoing and other objects in view, the invention consists in the novel construction, combination and arrangement of parts, as hereinafter more particularly described and claimed, and as illustrated in the accompanying drawings, wherein are shown preferred embodiments of my invention, but it is to be understood that such description and drawings are to be taken as illustrative, rather than limitative.

In the accompanying drawings in which like numerals are employed to designate like parts throughout the same:—

Figure 1 is a perspective view of a brake beam hanger constructed in accordance with this invention.

Figure 2 is an edge elevation thereof.

Figure 3 is a side elevation thereof.

55 Figure 4 is a perspective view of a modified form of hanger member.

Figure 5 is a perspective view of a further modified form of hanger member.

Figure 6 is a perspective view of a further 60 modified form of hanger member.

Figure 7 is a perspective view of a further modified form of hanger member.

Referring to Figures 1, 2 and 3 of the drawings, the numeral 1 designates generally a 65 hanger member known in the art as U type, and consisting of a pair of parallel, vertical arm portions 2 and 3 connected together at their lower ends by means of a horizontal portion 4. The arm 2 is formed at its upper 70 end with an eye 5, the aperture 6 of which extends at a right angle to the arm 2 and is disposed in the vertical plane of the arm.

Spaced from the upper end thereof, the arm 3 is formed with an eye 7, the aperture 8 of which extends at a right angle to the arm 3 and is disposed in the vertical plane of the arm 3. The eyes 5 and 7 are disposed in opposing, spaced relation with the apertures 6 and 8 in registry. The free end portion of 80 the arm 3 extends laterally from the eye 7 to form a horizontal projection 9 which is slightly offset with respect to the vertical plane of the arm 3. The projection 9 is disposed with a portion of its longitudinal surface flush 85 with a portion of the wall surface of the aperture 8.

Extending through the eyes 5 and 7 is a pin 10 which is formed at one end with an eye 11 extending at a right angle to the pin. 90 The aperture 12 extending through the eye 11 is offset with respect to the vertical plane of the arm 3 and is out of registry with the apertures 6 and 8 but the plane thereof extends in parallel relation to the planes of the apertures 6 and 8. When the hanger member 1 and pin 10 are assembled with the pin extending through the eyes 5 and 7, the projection 9 extends through the eye 11 and projects laterally therefrom. With the hanger 100

member 1 and pin 10 in assembled relation, the eyes 7 and 11 coact with the pin 10 and projection 9 respectively to prevent any rotation of the pin 10 with respect to the hanger member 1.

Extending transversely through the projection 9 in a vertical direction is an opening 13 for the reception therethrough of a vertically disposed cotter key 14. With the cotter key 14 in place, the eye 11 is prevented from being removed from the projection 9 and the hanger member 1 and pin 10 are thereby securely locked in assembled relation. Spaced outwardly from the eye 5, the pin 10 is formed with an opening 15 extending transversely therethrough in a vertical direction for the reception therethrough of a vertically disposed cotter key 16. With the cotter key 16 in place, the eye 11 is prevented from being removed from the projection 9 and the hanger member 1 and pin 10 are thereby securely locked in assembled relation.

The cotter keys 14 and 16 provide a double locking means for securing the hanger member 1 and pin 10 in assembled relation as each is capable of performing this function independently of the other. Thus if one of the keys should for any reason become displaced, the other key would function to prevent the relative displacement of the hanger member 1 and pin 10.

With the pin 10 locked against rotary movement with respect to the hanger member 1, and with the cotter keys permanently maintained in a vertical position, practically all possibility of the keys becoming inadvertently dislodged is eliminated.

Referring to Figure 4 of the drawings, the hanger member 17 is in the form of a hook having an upturned lower end 18 and having an eye 19 formed in spaced relation to its upper end, said upper end terminating in a horizontally projecting portion 20.

Referring to Figure 5 of the drawings, the hanger member 21 is in the form of a stirrup having an arm 22 extending upwardly therefrom and formed with an eye 23 and a horizontal projection 24 in the same manner as the member 17 described in connection with

Figure 4.

Referring to Figure 6 of the drawings, the hanger member 25 is formed with a vertical arm 26 having an eye 27 and a horizontal projection 28 formed therewith. The member 25 is further formed with an angularly disposed arm 29, which is formed at its upper end with a vertically disposed eye 30 which is in alignment with the eye 27 with the apertures 31 through the eyes 27 and 30 in registry.

Referring to Figure 7 of the drawings, the hanger member is formed with a horizontal portion 31 having a pair of vertical arms 32 and 33 formed integral therewith, with the arms 32 and 33 merging into a pair of angularly disposed, converging portions 34 and

35. The portion 35 is formed with a vertically disposed eye 36 and terminates in a horizontal projection 37. The portion 34 is formed at its upper end with a vertically disposed eye 38 which is in alignment with the eye 36 and the apertures 39 through the eyes 36 and 38 are in registry. 70

Each of the hanger members illustrated in Figures 4 to 7 is adapted to have associated therewith a hanger pin of appropriate length 75 and formed with an eye in the same manner as the pin 10 described in connection with Figures 1 to 3.

It is thought that the many advantages of a brake beam hanger in accordance with this invention will be readily apparent, and although the preferred embodiments are as illustrated and described, yet it is to be understood that various changes may be made in the details of construction, which fall within the scope of the invention as defined in the appended claims. 80

What I claim is:

1. In a brake beam hanger, a hanger member formed with an eye and having a laterally projecting end portion in proximity to said eye, and a hanger pin for insertion through said eye and formed at one end with an offset eye for the reception therethrough of said projecting end. 90

2. In a brake beam hanger, a hanger member formed with an eye and having a laterally projecting end portion in proximity to said eye, and a hanger pin for insertion through said eye and formed at one end with an offset eye for the reception therethrough of said projecting end, said projecting end and offset eye being disposed at right angles to each other. 100

3. In a brake beam hanger, a hanger member formed with an eye and having a laterally projecting end portion in proximity to said eye, and a hanger pin for insertion through said eye and formed at one end with an offset eye for the reception therethrough of said projecting end, said projecting end having a portion of its longitudinal surface flush with a portion of the wall surface of said hanger member eye. 110

4. In a brake beam hanger, a hanger member formed with an eye and having a laterally projecting end portion in proximity to said eye, and a hanger pin for insertion through said eye and formed at one end with an offset eye for the reception therethrough of said projecting end, said projecting end and pin each being formed with a transverse opening extending therethrough in a vertical direction. 120

5. In a brake beam hanger, a hanger member including an arm formed with an eye having the opening therethrough extending in a horizontal direction, said arm having an end portion adjacent said eye and extending at a right angle thereto, and a hanger pin 130

for insertion through said eye and having a right angularly offset eye for the reception therethrough of said end portion of the arm.

6. In a brake beam hanger, a hanger member including an arm formed with an eye having the opening therethrough extending in a horizontal direction, said arm having an end portion adjacent said eye and extending at a right angle thereto, and a hanger pin for insertion through said eye and having a right angularly offset eye for the reception therethrough of said end portion of the arm, said eyes being out of registry and out of alignment in their lateral and vertical planes.

15. 7. In a brake beam hanger, a hanger member including an arm formed with an eye having the opening therethrough extending in a horizontal direction, said arm having an end portion adjacent said eye and extending

20 at a right angle thereto, and a hanger pin for insertion through said eye and having a right angularly offset eye for the reception therethrough of said end portion of the arm, said end portion and pin each being formed with

25 a transverse opening extending therethrough in a vertical direction, and a cotter key for insertion through each of said transverse openings, each of said cotter keys independently coacting with said hanger member and pin 20 for maintaining them in assembled relation.

30 for maintaining them in assembled relation.

8. A hanger pin comprising an elongated shank having an end portion thereof bent to provide a right angularly offset eye, said shank being formed adjacent its other end with a transverse opening, said opening extending in a plane substantially parallel with the plane of said offset portion.

In testimony whereof, I affix my signature
hereto.

GEORGE W. MILLER.
